AIR COOLER

Filed Sept. 2, 1939

UNITED STATES PATENT OFFICE

2,207,313

AIR COOLER

Garland N. Crouch, Oklahoma City, Okla.

Application September 2, 1939, Serial No. 293,298

2 Claims. (Cl. 62—131)

This invention relates to air coolers, and it is a particular object of the invention to provide a device of this kind to be placed within an enclosed body of a truck or the like to maintain the air within said body at a relatively low temperature.

It is also an object of the invention to provide a device of this kind comprising a box containing the desired cooling medium, such as ice, and wherein means are provided for causing air within the body of a truck or kindred chamber to travel in a tortuous path thru the box for discharge within the box or chamber.

The invention consists in the details of construction and in the combination and arrangement of the several parts of my improved air cooler whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing wherein

Fig. 1 is a view partly in vertical section and partly in elevation illustrating an air cooler constructed in accordance with an embodiment of my invention, the line of section being substantially on the line 1—1 of Fig. 2.

Fig. 2 is a transverse sectional view on substantially the line 2—2 of Fig. 1.

My improved device as herein disclosed comprises a box B of desired dimensions and which is adapted to be placed within the enclosed body of a truck or other chamber and adjacent to an end wall of such body or chamber. The top portion of the box B at one end thereof and at a point at substantially its center is provided with the transversely disposed flat members or panels 1 and 2. The space between the panels 1 and 2 is adapted to be closed by a removable door 3 while the space between the member or panel 2 and the end of the box B remote from the member or panel 1 is adapted to be closed by the door 4. The doors 3 and 4 provide means whereby ice may be readily placed within the box B.

Extending upwardly from the member or panel 2 is a riser pipe 5 which is preferably of a length to closely approach the top or roof of the closed body or chamber. The upper end of the riser pipe 5 is continued by a horizontally disposed

pipe or conduit 7 of a length to terminate at approximately the center of the body or chamber. The outer end portion of this pipe or conduit 7 is provided with a discharge nozzle herein disclosed as of a type to discharge the air therefrom in diverging streams. It is to be stated at this time, however, that insofar as the present invention is concerned, the exact location of the nozzle with respect to the body or chamber in which it is positioned forms no essential part of the invention as such nozzle may be positioned where it is believed the best results can be obtained.

Extending within the box B thru the member or panel 1 is a desired number of air intake pipes 8. The lower end portion of each of these pipes 8 is in communication from above with a manifold 9 of desired length and preferably of a length to substantially bridge the space between the side walls 10 of the box B but spaced therefrom sufficiently to allow ice water or brine to substantially completely surround the manifold.

The inner wall 11 of the manifold 9 has in communication therewith a plurality of spaced parallel flues 12 arranged side by side and which also communicate with a second manifold 14 thru the inner wall 15 thereof. This manifold 14 also extends substantially entirely from one side wall 10 of the box B to the other. The manifold 14 is of a size to depend a material distance below the flues 12 and the manifold 14 below the flues 12 has in communication therewith thru its inner wall 15 a second series of flues 16. These flues 16 are in parallelism and are arranged side by side in such spaced relation whereby the flues 12 and 16 are staggered. The flues 16 are also in communication with a manifold 17 thru the inner wall 18 thereof. This manifold 17 is positioned below the manifold 9 and is of substantially the same length as the manifold 9.

Underlying the manifolds 14 and 17 and also the flues 16 is a duct 19 of a width substantially equal to the widths of the manifolds 14 and 17. One end portion of the duct 19 is in communication, as at 20, with the manifold 17 thru the bottom wall 21 thereof. The duct 19 at its extremity remote from the manifold 17 is continued by a vertically disposed duct 22 which passes between the manifold 14 and the adjacent end wall 23 of the box B. This vertical duct 22 extends a desired distance above the manifold 14 and has communication with a fan housing 24 thru the bottom wall 25 thereof.

Suitably supported within the opposite end

portions of the housing 24 are the suction fans 26 of a conventional type and driven in any manner desired altho it is preferred that the same be driven by an electric motor in communication 5 with a battery or other suitable source of electrical energy.

The fans 26 include discharge nozzles 27 which extend out thru the inner wall 28 of the housing 24 and discharge within the upper portion of the 10 box B.

It is to be pointed out that the flues 12 and 16 are each in cross section in the form of an inverted V. This allows for quick chilling and by having the flues 16 in staggered relation allowance is 15 made for all of the flues to have close contact with the ice as the ice melts and drops.

It is also to be pointed out that the arrangement of the flues 12 and 16 together with the ducts 19 and 22 is such as to assure quick chilling of the 20 air as it is drawn therethru by the fans 26. By having the nozzles 27 discharge within the upper portion of the box B the melting of the ice within the box B is sufficiently retarded to render the use 25 of the apparatus highly economical.

It is further to be stated that the closure members or doors 3 and 4 when applied effect airtight closures and it is to be pointed out that the efficiency of the apparatus is further increased by 30 having the fans 26 contained within the housing 24.

From the foregoing description it is thought to be obvious that an air cooler constructed in accordance with my invention is particularly well adapted for use by reason of the convenience and 35 facility with which it may be assembled and operated, and it will also be obvious that my invention is susceptible of some change and modification without departing from the principles and spirit thereof and for this reason I do not wish to be 40 understood as limiting myself to the precise arrangement and formation of the several parts herein shown in carrying out my invention in practice except as hereinafter claimed.

I claim:

1. An air cooler comprising an enclosed box, a

discharge pipe leading from the upper portion of the box, two manifolds in one end portion of the box, one of said manifolds being positioned above the other, a single manifold in the opposite end portion of the box, flues interposed between and connecting the uppermost of the first named manifolds with the single manifold, flues connecting the single manifold with the lower of the first two manifolds, the upper of the first two manifolds being in communication with the outside 5 atmosphere, a duct underlying the second named flues and in communication with the lower of the first named manifolds, said duct being continued by a vertically disposed duct, a housing within the upper portion of the box with which the 10 vertically disposed duct communicates, and a suction fan within the housing for drawing outside air thru the manifolds, flues and ducts and delivering such air within the upper portion of the box for discharge thru the discharge pipe. 15

2. An air cooler comprising an enclosed box, a discharge pipe leading from the upper portion of the box, two manifolds in one end portion of the box, one of said manifolds being positioned above the other, a single manifold in the opposite end portion of the box, flues interposed between and connecting the uppermost of the first named manifolds with the single manifold, flues connecting the single manifold with the lower of the first two manifolds, the upper of the first two manifolds being in communication with the outside 20 atmosphere, a duct underlying the second named flues and in communication with the lower of the first named manifolds, said duct being continued by a vertically disposed duct, a housing within the upper portion of the box with which the vertically disposed duct communicates, and a suction fan within the housing for drawing outside air thru the manifolds, flues and ducts and delivering such air within the upper portion of the box for discharge thru the discharge pipe, each of the flues in cross section being substantially in the 25 form of an inverted V. 30
